(57) **CLAIM**

The ornamental design for an automotive trim part having a bi-component show surface, as shown and described.

DESCRIPTION

FIG. 1 is a perspective view of the automotive trim part having a bi-component show surface of the present invention;

FIG. 2 is a top plan view of the automotive trim part having a bi-component show surface shown in FIG. 1;

FIG. 3 is a bottom plan view of the automotive trim part having a bi-component show surface shown in FIG. 1;

FIG. 4 is a right hand side elevational view of the automotive trim part having a bi-component show surface shown in FIG. 1;

FIG. 5 is a left end elevational view of the automotive trim part having a bi-component show surface shown in FIG. 1; and,

FIG. 6 is a right end elevational view of the automotive trim part having a bi-component show surface shown in FIG. 1. FIGS. 2 and 3 are shown broken away for ease of illustration. FIGS. 5 and 6 are shown on an enlarged scale as compared to FIG. 1.
